CIRCUIT BREAKER

Howard M. Strobel, New York, N. Y.

Original application June 8, 1945, Serial No. 598,269, now Patent No. 2,564,178, dated August 14, 1951. Divided and this application July 16, 1951, Serial No. 236,995

7 Claims. (Cl. 200—147)

1

This invention relates to deionization type of electrical circuit breakers in which the extended arc path of relatively low resistance resulting from separating movable contacts is divided into a plurality of smaller arc elements of relatively high resistance.

In my application Serial No. 598,269, filed June 8, 1945, now Patent No. 2,564,178, issued August 14, 1951, I disclosed several deionization circuit interrupter structures wherein the magnetically deflected arc elements are moved along different types of predetermined paths. This patent application is a division of the aforesaid patent application.

The primary object of the invention is to provide improved apparatus and method for increasing the number of subdivisional arc elements that may be formed in a deionization circuit breaker where certain dimensions of size are limited by practical space considerations, and to provide therein improved method and means for magnetically deflecting arc elements along predetermined paths.

In the conventional deionization circuit breaker the main arc, which is drawn out between the separable arcing contacts, is moved into an arc receiving means comprising spaced conducting plates adapted to subdivide the main arc into a plurality of smaller primary arcs. The geometry of the spaced conducting plates defines the form of path that the smaller primary arcs are to be moved along. The path so defined may be open-ended, as when the final arc movement is translational, or recurrent, as when each primary arc is finally rotated like a cylindrical element or like a radial element along a substantially circular path.

A more specific object of my invention is the provision of improved apparatus for a circuit interrupter having a plurality of deionization units racked side-by-side in series connection, each of said units having two successive arrays each of which includes a plurality of spaced conducting arc splitting members, the first array of each unit being formed preferably of substantially two spaced parallel planes plates with arc receiving means arranged substantially transverse to the main arc path and having a suitable deflective means or magnetic circuit adapted to move the main arc into its arc receiving means, whereby the main arc is moved into the arc receiving means of the first array of each deionization unit and separated into as many short or primary arcs as there are deionization units in series, and connecting means being provided be-

5 tween the first and second arrays of each deionization unit so that each of said primary arcs in moving successively from one array to the other is extended and oriented to a position substantially askew to and at right angles to the main arc path, the second array of each deionization unit having arc receiving members arranged substantially transverse to the extended and oriented primary arcs and having provided a suitable deflective means or magnetic circuit adapted to move each of the extended and oriented primary arcs into its respective arc receiving means, whereby each extended and oriented primary arc is moved into the arc receiving means of the second array of each deionization unit and further separated into a plurality of shorter or secondary arcs which are then made to move along a recurrent path as defined by the arc running members of each deionization unit of the improved apparatus until extinguished.

10 More particularly, the invention consists in the system and method hereinafter described, illustrated in the accompanying drawings and defined in the claims hereto appended, it being understood that various changes in form, arrangement and details both of circuits and of method within the scope of the claims may be resorted to without departing from the spirit or sacrificing any of the advantages of the invention.

15 A clearer understanding of the operation of the invention and its improvement over known methods can be obtained by reference to the following figures and the descriptions relating thereto.

20 Fig. 1 is a pictorial view of one section or unit of the improved deionization device whose structure is adapted to define the paths of the arc elements to give final radial rotation in a recurrent path.

25 Fig. 2 shows two of the conductive cylindrical pieces used in the device of Fig. 1.

30 Fig. 3 shows three of the insulative pieces which are used in supporting the conductive cylindrical pieces of Fig. 1.

35 Fig. 4 shows pictorially the flow of current through a circuit breaker using a plurality of the units shown in Fig. 1.

40 Fig. 5 shows a view partly in section and partly in elevation of the arc extinguisher of my invention which uses six deionization units substantially similar to the one in Fig. 1; the section has been taken along the line V—V in the plan view of Fig. 6.

45 Fig. 6 shows a plan view of an arc extinguisher with six of the improved deionization units

(which are substantially similar to the one in Fig. 1) assembled in series.

Fig. 7 is a cross sectional view through the arc extinguisher of Fig. 5 taken along the line VII—VII.

Fig. 8 is a cross sectional view through the arc extinguisher of Fig. 5 taken along the line VIII—VIII.

Fig. 9 is a cross sectional view through the de-ionization unit 30c of Fig. 5 taken along the line IX—IX.

Fig. 1 shows a structure for defining the paths and motions of the arc elements to give final radial rotation thereof in a plurality of concentric circular recurrent paths. The primary arc splitting plates are indicated by 31 and 32. The inner cylindrical metallic member 33 is joined to the upper end of metallic plate 31, and the outer cylindrical metallic member 34 is joined to the upper end of metallic plate 32. The insulating members 29, 35 and 36 are adapted to support the cylindrical secondary arc splitting plates 37a, and 37b. For clarity, only two cylindrical plates 37 are shown here, although it is obvious that as many such cylindrical plates 37 can be used as considerations of spacing and size permit. (In Figs. 5 to 9, for example, five concentric cylindrical secondary plates 37a to 37e have been used.) Piece 19 is an insulative baffle. The numbers 38 and 39 indicate the edges of the primary arc splitting plates 31 and 32 (or 34) which serve as arcing guides to extend and orient the primary arc existing between the points 40 and 41.

Referring to Fig. 1, it is noted that the cylinders which serve as the secondary arc splitting plates are formed by cutting out a 180° sector from the cylinders as shown. This would require that the extended and oriented primary arc element should be in a vertical radial position as it entered the secondary arc splitting plates. However, as a matter of practical design, it might be more desirable that the said primary arc element should be in a horizontal radial position and be moving upwards as it entered the secondary arc splitting plates. (The units 30 shown in Figs. 5 to 9 are made in this manner.) The cutting out of the 180° sector from the cylinders as shown here in Fig. 1 served to clarify the drawings and the description of the operation of the device. However, by cutting out a 90° sector from all of the cylinders, as indicated by the dotted line extension of the cylinders 37a and 37b in Fig. 2 and as shown in Figs. 5 to 9, the primary arc element would be in a horizontal position while entering the secondary arc splitting plates. With such a construction, of course, it would be necessary to modify pieces 35 and 36 as to their shape and the locations of the venting holes as is shown in Figs. 7 and 8. These minor mechanical details are more or less obvious. Also, the arc receiving means of 37 may be notched similar to 37b of Fig. 2, or similar to 31 of Fig. 1.

Fig. 2 shows the conductive cylindrical secondary arc splitting plates 37a, 37b. Fig. 3 shows the three insulative members 35, 29 and 36 in the same relative space positions that they occupy in the assembled unit 30 shown in Fig. 1. These members are provided with grooves to retain and support the cylindrical members 33, 34, 37a and 37b.

Figs. 5 to 9 show elevation, plan and cross sectional views of an arc extinguisher using six de-ionization units 30a to 30f. Each of these de-ionization units is similar to the one shown in

perspective in Fig. 1, except that five cylindrical secondary arc-splitting plates 37a to 37e are shown in lieu of the two shown for descriptive purposes in Figs. 1 and 2. The identifying numbers 5 used to indicate the parts of unit 30 in Fig. 1 are also used to indicate the same parts in Figs. 5 to 9. Referring to Figs. 5 to 8, the uprights 21a, 21b are made of insulating material and support the cross pieces 20a and 20b, also made of insulating material, to form a box or rack to hold the six de-ionization units 30a to 30f. The arcing horns 27 and 28 are bolted to the uprights 21b and 21a respectively, as shown. The stationary contact 24 is supported from the arc horn 27 but insulated therefrom by the block of insulation 18. The moving contact 25 may be actuated to open position by any suitable type of operating mechanism which may be provided with main contacts for normally completing the circuit through the 10 circuit breaker. The line terminal 22 of the circuit connects to the stationary contact 24 and the other line terminal 23 to the arc horn 28 and the moving contact 25. The coils 61a and 61b of Figs. 5, 6 and 7 are positioned in grooves provided in the insulating cross pieces 20a and 20b. When energized, the coils 61a and 61b provide a magnetic field transverse to the path of the main arc and thus deflect the main arc into and past the primary arc splitting plates 31 and 32 of each 15 de-ionization unit 30. The coils 61a and 61b are connected in series by the jumper 60a (Fig. 7), with one end of the coil 61b connected to the stationary contact 24 through the conductor 60 (Figs. 5 and 7), and the other end of coil 61a 20 connected to arc horn 27 through the conductor 60b (Fig. 7). The coils 64a and 64b of Figs. 5 and 6 are positioned in grooves provided in the insulating uprights 21a and 21b. When energized, the coils 64a and 64b create a magnetic 25 field through the secondary array of concentric cylinders of such directions as to be parallel to the common axis of the cylinders and thus transverse to the paths of the secondary radial arc elements formed between the cylindrical secondary 30 arc splitting plates 37 in each de-ionization unit 30. The coils 64a and 64b are connected in series by the jumper 63a (Fig. 5), with the other end of coil 64a connected through conductor 63 to the end secondary arc switching plate 37a of de-ionization unit 30a (Fig. 5), and the other end of coil 64b returned to line terminal 23 through the conductor 63b (Fig. 5).

Referring to Fig. 5, when the arcing contacts 24, 25 are separated an arc is formed between 25 them and the current flow is line terminal 22 to stationary contact 24, to movable contact 25, and return to line terminal 23. The arc flame is then moved upward between the arc horns 27 and 28, the transfer of one end of the arc from stationary 30 contact 24 to arc horn 27 automatically switching in coil 61 so that the line current must now flow from line terminal 22, to stationary contact 24, through conductor 60, coil 61 to arc horn 27, and thence through the arc to arc horn 28 and return 35 to the line terminal 23. The connections and current flow through the coil 61 are such as to create a horizontal magnetic field transverse to the main arc discharge. The arrow 62 in Figs. 1 and 4 indicates the direction of the magnetic field H produced by the coil 61. Referring back to Fig. 5, the magnetic field deflects the arc flame upwards into the primary arc splitting plates 31, 32 of each of the six de-ionization units 30a to 30f shown. The main arc is thus divided 40 into a plurality of shorter arcs or primary arcs 45 into a plurality of shorter arcs or primary arcs 50 into a plurality of shorter arcs or primary arcs 55 into a plurality of shorter arcs or primary arcs 60 into a plurality of shorter arcs or primary arcs 65 into a plurality of shorter arcs or primary arcs 70 into a plurality of shorter arcs or primary arcs 75 into a plurality of shorter arcs or primary arcs

by the six deionization units 30a to 30f. In this regard, it is to be pointed out that the apparatus and method used to create and deflect the main arc into the primary arc splitting plates, where it is divided into a plurality of primary arcs, follow conventional practice and are well known to the art. According to this invention (the deionization unit 30 of Fig. 1), the primary arc existing between each pair of primary arc splitting plates 31, 32 of each deionization unit 30 (Fig. 1 or 5) is then moved upwards, extended and oriented to a line of position above and substantially at right angles to the line of position of the original primary arc. Each extended and reoriented primary arc is then moved into the arc receiving means of the secondary array of its deionization unit 30 where it is further subdivided into a plurality of secondary arc elements. These secondary arc elements are then rotated radially by magnetic means in a recurrent circular path as defined by the concentric cylinders of the secondary array until the arc is extinguished.

By referring to the perspective view of one of the deionization units 30 shown in Fig. 1 it will become clear how the structure of a deionization unit 30 extends, orients, and further subdivides each primary arc element into a plurality of secondary arc elements and then causes them to rotate radially along a circular recurrent path. As mentioned above, when the main arc strikes the primary arc splitting plates 31 and 32 it is subdivided to form a primary arc element between plates 31 and 32. The primary arc element moves upward between these plates until the hot spot 40 on plate 31 reaches the arcing runner 33, and the hot spot 41 on plate 32 reaches the arcing runner 39. Since the primary arc between 40 and 41 is still being deflected upwards by the magnetic field, the hot spot 40 moves along 30 to point 40a, while hot spot 41 moves along 39 to point 41a. It will be noted that this movement of the arc hot spots along the arcing runners results in both extending the primary arc and in substantially reorienting it to a position substantially at right angles to the direction of the main arc. Ultimately the hot spot 40 reaches the inner cylindrical member 33 of plate 31, and hot spot 41 reaches the outer cylindrical member 34 of plate 32. In this position, it will be noted that the primary arc has been extended between the cylinders 33 and 34, and reoriented to a radial position substantially at right angles to the main arc. As the extended and oriented primary arc is further deflected by magnetic or mechanical means, it will strike the arc receiving edges of the secondary arc splitting plates 37a and 37b, which then subdivide the primary arc into a plurality of radial secondary arc elements. It is to be noted that the secondary arc elements are radial to the axis of the cylinders, so that when a magnetic field 65 is applied parallel to the axis of the cylinders the radial secondary arc elements are rotated counterclockwise between the surfaces of the cylindrical members. The insulative end piece 35 (see Fig. 3) has its inside surface cut as a spiral wedge, which serves to guide the radial secondary arc elements along the axis into the cylindrical region of unit 30 between the disc like insulative members 29 and 36. In this region the secondary arc elements can be radially rotated by the magnetic field 65 around the circular recurrent path defined by the concentric cylinders until extinguished. As shown in Fig. 3, the end disc 36 can be pro-

vided with slots to aid in venting the air heated by the arcs.

A plurality of the units 30 shown in Fig. 1 can be racked side by side in a supporting box like structure 20-21, Figs. 5 to 7. When properly racked the axis of each unit 30 will line up along a common line, and each insulative end member 36 and metal plate 32 will be pressed against the plate 31 of the adjacent unit 30. When so racked, if we consider two units 30a and 30b, with unit 30a in front of unit 30b, it will be noted that the piece 35(b) of the back unit will be next to the piece 36(a) of the front unit so as to cover up the left hand side of piece 36(a). For this reason, no vent holes are shown in the left hand side of the insulative piece 36. However, it will be observed that the insulative piece 35 can be cut thinner at its lower half so as to provide space for additional venting holes in piece 36 if required.

It is to be noted that the cylindrical plates 37 and the end plates 33, 34 which make up the secondary array of arc splitting plates in Figs. 1 and 5 to 9 constitute a closed loop. Furthermore, if the deionization units 30 are used to interrupt alternating currents the coils which supply the magnetic deflecting fields must also be energized with alternating currents. As a result, the varying magnetic fields will induce eddy currents in the closed loops of the cylindrical plates 33, 34 and 37 by transformer action. These eddy currents may be prevented by the conventional method of cutting a longitudinal slot in each cylindrical member which forms a closed loop, taking care to stagger the position of each slot with respect to the position of the slots in adjacent cylinders. It will be obvious, of course, that when the deionization units 30 are used to interrupt direct current circuits this problem will not arise, and the slots may be omitted.

Fig. 4 is a schematic sketch of the flow of current through a deionization circuit breaker utilizing a plurality of units 30 (30a, 30b, 30c, etc.). The coils (61 and 64 in Figs. 5, 6 and 7) for producing the indicated magnetic fields H, arrows 62 and 65, are not shown here. The numbering of the parts in Fig. 4 corresponds substantially to those used in Figs. 1, 2, and 5 to 9. The diagram shows the flow of current through the units 30 after the main arc has been finally subdivided into secondary arc elements which are being radially rotated in a circular path defined by the concentric cylindrical surfaces of the device. At this time, the current (instantaneous) flow is, as indicated by the current arrows, along 50, 51, 52 to 33, 53 to 37a, 37b, 34, along 54 to 32, and so on through the succeeding units 30.

The above describes the basic operation of my improved deionization circuit breaker as applied to the structure shown. In the interest of clarity in the drawings the members of the various structures and their basic operative positions have been depicted as simply as possible, in order to better illustrate the essential character of the invention. As a matter of practical construction, it is obvious that the insulative members supporting arc splitting members can be slotted and grooved to receive the edges of the arc splitting members, and thus assist in preventing the arc flame from flashing around the arc splitting members. In order to assist in guiding the moving arc elements along the arc running paths in the various structures as are defined by the conducting arc splitting members and the sides of their insulative supporting members, the

surface of the conducting members can be given a central raised contour along the line of the defined arc running path. In the drawings the conducting members are shown with square edges, but it is obvious that these could be formed with their edges rounded in such a manner as to reduce the concentration of voltage stresses. Similarly, mechanical changes can be made in notching the arc receiving means of the plates, in making provisions for venting, and for preventing creepage and voltage breakdown in accordance with principles commonly employed in the art, without departing from the spirit of the invention as shown and described.

In the drawings shown the various structures have been adapted to extend and orient the primary arc element to a line of position substantially at right angles to the line of the main arc before dividing each primary arc into secondary arc elements. It is obvious that the 90° angle of orientation of the primary arc element as shown is not a necessary restriction. For example, in Figs. 1 and 5 the secondary array is shown oriented at a 90° angle with the line of the primary array, but as far as electrical considerations are concerned, could just as well be at some other angle, such as 45°, for example. As a matter of practical construction, however, the structure shown with the 90° angle of orientation is simpler than that which would be required by some other angle of orientation.

In the illustrations given the arc is deflected into arc splitting members arranged in two successive arrays, which are designated as a primary array and a secondary array. Two arrays substantially as described give a relatively simple physical construction of the device, and permit ready extension and orientation of the arc to a line of position in space where an array comprising a plurality of secondary arc splitting members can be conveniently formed. However, it is readily apparent that arc splitting members could be introduced at intermediate positions between the original position of the primary arc and the final position of the successively extended and oriented arc. Such an increase in the degree of arrays would follow readily from the ideas disclosed in this invention, but from a practical viewpoint it is apparent that such an operational cascading of arrays would result in a more complex physical structure.

The use of this invention, in which a portion or element of the arc is extended and oriented to a position which permits the use of increased number of arc splitting members, gives rise to many advantages. The arc splitting members can be constructed from sheets of conducting material formed into flat or cylindrical shapes. That is, the curved cylindrical surfaces required are developable surfaces which can be cut out or developed from flat sheet metal stock and then rolled or curved into the desired cylindrical surfaces. The use of an increased number of arc splitting members for a given consideration of size and space enables the device to interrupt greater voltages and currents than would otherwise be possible. The device of Fig. 1 provides for a recurrent circular arc running path, in which the secondary arc elements are rotated radially. It will be observed that a simple transverse magnetic field parallel to the axis of the cylinders is all that is required to give the desired recurrent radial rotation of all the final secondary arc elements. Because of the cylind-

rical construction of the secondary array of the deionization units 30, Figs. 1 and 5, the coil turns required to produce this longitudinal magnetic field (65 in Fig. 1) could very conveniently be wound around the cylinder 34 of each unit 30 so that when they are racked as shown in Fig. 5 a uniform longitudinal magnetic field would result.

I claim:

- 10 1. In a circuit interrupter, means for drawing a main arc between a pair of separable contact members, means for dividing said main arc into a plurality of series related primary arc elements, means for extending and orienting at least one of said primary arc elements to a position substantially at right angles to the main arc path, means for dividing at least one of said oriented primary arc elements into a plurality of series related secondary arc elements, and means for radially rotating at least one of said secondary arc elements along a closed recurrent arc running path between spaced conducting members around an axis substantially parallel to that of the main arc path until extinguished.
- 15 2. In a circuit interrupter, a primary series array of parallel spaced conducting members, a secondary array of spaced conducting members for substantially each pair of members in the primary series array, said primary series array being positioned along a line substantially parallel to and above that of the main arc path and having the plane of the arc receiving means of its conducting members in a plane substantially transverse to the main arc path, said members of substantially each of said secondary arrays comprising a plurality of substantially concentric conducting cylinders, the common axis of said concentric cylinders being substantially parallel to the main arc path, substantially each of said cylinders having a longitudinal offset portion adapted to receive a primary arc element and to subdivide it into series related secondary arc elements, means for drawing a main arc between a pair of separable contact members, means for causing said main arc to pass into the arc receiving means of the primary array where it is subdivided into a plurality of series related primary arc elements, means for causing substantially each primary arc element to be extended and oriented so as to pass into the arc receiving means of a secondary array where it is subdivided into a plurality of series related radial secondary arc elements, and means for causing substantially each radial secondary arc element to move along a substantially circular arc running path as defined by its pair of spaced conducting concentric cylinders in the secondary array until extinguished.
- 20 3. In a circuit interrupter, a primary series array of parallel spaced conducting primary members, a secondary array of concentric spaced conducting secondary members for substantially each pair of primary members, said primary members including substantially plane flat plates with a lower portion thereof adapted to receive and series divide an arc, the plane of the arc receiving portion of said primary members being arranged substantially transverse to and above the main arc path, substantially each pair of primary members having an extension for each primary member adapted to form a pair of spaced and substantially concentric end plate secondary members in said secondary array, each of said end plates including substantially a cy-

- 75

cylindrical surface with a portion thereof adapted to receive the terminal end of an arc, the plane of the arc receiving portion of said end plate members being arranged substantially vertical and at an angle to the plane of the arc receiving portion of its primary member, the adjacent surfaces of said cylindrical end plates being spaced substantially parallel to each other, the spacing between said cylindrical end plates being greater than the spacing between their respective primary plates, a plurality of spaced conducting secondary members arranged concentrically between each pair of said cylindrical end plate members and having their active surfaces substantially parallel to those of said end plate members, said secondary members comprising substantially concentric cylindrical plates with a longitudinal offset portion thereof adapted to receive and series divide an arc, means for drawing a main arc between a pair of contact members, means for causing said main arc to pass into the arc receiving means of the primary array where it is subdivided into a plurality of series related primary arc elements, means for causing substantially each primary arc element to be extended and oriented so as to pass into the arc receiving means of a secondary array where it is subdivided into a plurality of series related radial secondary arc elements, and means for causing substantially each secondary arc element to move as a radial element along a substantially circular recurrent arc running path as defined by the active surfaces of its pair of spaced concentric cylindrical members in the secondary array until extinguished.

4. In an arc extinguisher, a pair of parallel substantially plane primary members and a plurality of substantially concentric cylindrical secondary members, said members being formed of conducting material, said conducting members being spaced and supported by insulative members with the plane of the primary members being substantially transverse to the common axis of the concentric cylindrical secondary members, said insulative members defining an endless path between substantially each pair of secondary members, defining an approach path extending from adjacent the point where the arc is established between the primary members to the arc receiving means of the secondary members, and defining a helicoidal path extending from the point where an arc is established between a pair of secondary members into said endless path, and means for setting up a magnetic field for moving the arc along said approach and helicoidal paths into said endless path and for rotating the arc to move it along said endless path.

5. In an arc extinguisher, a pair of parallel substantially plane conducting primary members and a plurality of substantially concentric cylindrical conducting secondary members, the inner secondary member being conductively joined to one primary member, and the outer secondary member being conductively joined to the other of said primary members, substantially each intermediate secondary member hav-

- ing an offset portion and a notch to form an aligned groove in which the arc may play, said primary members having an arc approach path adapted to extend and orient the arc into a position adjacent to the arc receiving means of the secondary members, substantially each pair of a plurality of said secondary members having a recurrent arc path extending therearound at one side of said groove, means for moving the arc into the arc receiving means of said primary members, means for moving the arc along said arc approach path, and means for establishing a magnetic field longitudinally through said cylindrical conducting secondary members and across said groove for moving the arc into said cylindrical conducting secondary members and splitting it up into short series related arcs and for rotating said short arcs about said recurrent paths.
- 20 6. In a circuit interrupter, a pair of spaced pole areas defining a field in a magnetic circuit, a pair of stationary parallel spaced conducting primary members substantially parallel to said pole areas and having their upper extensions positioned in space between said pole areas, a plurality of concentric cylindrical conducting secondary members positioned longitudinally in said field and in the space between said upper extensions of said primary members, a plurality of said cylindrical secondary members having a helicoidal arc receiving portion, said primary members having an arc approach path adapted to extend and orient the arc into a position adjacent to the arc receiving means of the secondary members, means for initially establishing the arc in space adjacent to the arc receiving means of said primary members and transverse thereto, and means for setting up a magnetic field between said pole areas and across said arc establishing means for moving said arc from said means and establishing it first between said primary members and then in said approach path and finally among said cylindrical secondary members.
- 35 7. In an arc extinguisher, a primary and a secondary group of spaced conducting plates, said secondary group including sets of substantially cylindrical and concentric plates, a plurality of said plates in said secondary group being electrically insulated from the plates in the primary group and being positioned substantially in sets between pairs of primary plates with their surfaces substantially perpendicular to the plane of the surfaces of the plates in the primary group, substantially each end plate of a secondary set being connected to but one primary plate, and means for causing the arc to play with a part thereof first in the primary and then in the secondary group of said plates.
- 40 8. In an arc extinguisher, a primary and a secondary group of spaced conducting plates, said secondary group including sets of substantially cylindrical and concentric plates, a plurality of said plates in said secondary group being electrically insulated from the plates in the primary group and being positioned substantially in sets between pairs of primary plates with their surfaces substantially perpendicular to the plane of the surfaces of the plates in the primary group, substantially each end plate of a secondary set being connected to but one primary plate, and means for causing the arc to play with a part thereof first in the primary and then in the secondary group of said plates.
- 45 9. In an arc extinguisher, a primary and a secondary group of spaced conducting plates, said secondary group including sets of substantially cylindrical and concentric plates, a plurality of said plates in said secondary group being electrically insulated from the plates in the primary group and being positioned substantially in sets between pairs of primary plates with their surfaces substantially perpendicular to the plane of the surfaces of the plates in the primary group, substantially each end plate of a secondary set being connected to but one primary plate, and means for causing the arc to play with a part thereof first in the primary and then in the secondary group of said plates.
- 50 10. In an arc extinguisher, a primary and a secondary group of spaced conducting plates, said secondary group including sets of substantially cylindrical and concentric plates, a plurality of said plates in said secondary group being electrically insulated from the plates in the primary group and being positioned substantially in sets between pairs of primary plates with their surfaces substantially perpendicular to the plane of the surfaces of the plates in the primary group, substantially each end plate of a secondary set being connected to but one primary plate, and means for causing the arc to play with a part thereof first in the primary and then in the secondary group of said plates.
- 55 11. In an arc extinguisher, a primary and a secondary group of spaced conducting plates, said secondary group including sets of substantially cylindrical and concentric plates, a plurality of said plates in said secondary group being electrically insulated from the plates in the primary group and being positioned substantially in sets between pairs of primary plates with their surfaces substantially perpendicular to the plane of the surfaces of the plates in the primary group, substantially each end plate of a secondary set being connected to but one primary plate, and means for causing the arc to play with a part thereof first in the primary and then in the secondary group of said plates.
